Dec. 1002

T. H. Wood, J. E. Roberts of Utica, N. Y. & H. S. Hubbell of Buffalo, N. Y.
Letters Patent No. 1.002, dated May 11, 1858.

The schedule referred to in these Letters Patent and making part of the same.

To all whom it may concern:

Be it known that we Thomas H. Wood and John E. Roberts of the City of Utica, County of Oneida and State of New York, and Henry S. Hubbell, of the City of Buffalo, County of Erie, and State aforesaid have invented or produced a new and original design for a Cooking Stove called the "Baltic" and we do hereby declare that the following is a full and exact description of the same reference being had to the accompanying drawing and the letters of reference marked thereon.

Letters A, A, the Top Plate. B, B, upper and lower half Front. C, C, one of the Front Doors, both being the same. D, D, The Furnace or Fire Bed Hearth with Side Hearth, E, E, The side plate. F, F, the Oven Doors, G, the End Fire door, H, H, the Bottom Plate.

What we claim as our invention or production and desire to procure by Letters Patent, is the general design and configuration.
